FLARE ASSEMBLY

Clark M. Bolser, Des Moines, Iowa

Application May 2, 1936, Serial No. 77,503

8 Claims. (Cl. 67—55)

My invention relates to a flare assembly which is primarily intended for use with pleasure automobiles, but which may be used in a variety of other ways.

5 My object is to provide a container for liquid fuel and for one or more flares, which container has a top that can be fastened on so as to make the whole container leakproof.

A further object is to provide in connection 10 with this container one or more flares adapted to be dropped into the container, and so constructed that when they are submerged in the fuel in the container, they will be automatically filled with the fuel.

15 Another object is to provide such flares and container with cooperating means whereby the flares may be removed from the container without the necessity for putting the fingers of the user into the fuel in the container.

20 With these and other objects in view, my invention consists in the construction, arrangement and combination of the various parts of the device, whereby the objects contemplated are attained, as hereinafter more fully set forth, pointed 25 out in my claims, and illustrated in the accompanying drawing, in which:

Figure 1 is a perspective view of the front of an automobile equipped with a flare assembly embodying my invention.

30 Figure 2 is a vertical sectional view of such a flare assembly, the lower flare being illustrated in side elevation.

Figure 3 is a side elevation of the container; and

Figure 4 is a side elevation of one of the flares.

35 The use of flares in connection with the operation of trucks has become quite general. When the truck is compelled to stop on the highway, the trucker can light his flares and set them behind the truck and in front of the truck, and if he desires, at the side of the truck, for thus providing a warning signal and preventing accidents. Heretofore no flares have been produced for use 40 with pleasure cars. It is my present purpose to provide a flare assembly which can be readily provided and conveniently used with an ordinary automobile.

In the accompanying drawing I have used the reference numeral 10 to indicate generally a container in the form of a vertical elongated cylindrical can, preferably of sheet metal. The container 10 is preferably provided, a little above its middle from top to bottom, with an annular rib 11. At the top of the container is an annular outwardly extending flange 12. I have provided 55 for the container a dome shaped top or cap 13,

having a peripheral downwardly extending flange 14 adapted to set over the flange 12. I preferably glue on the inside of the cap 13 a gasket 15 adapted to rest on the flange 12 when the cap is on the container. The cap is preferably assembled 5 on the container in the following manner.

On the container below the rib 12 is an annular ring 16 having at its upper edge an annular, outwardly extending flange 17. On opposite sides the flange 17 has the upwardly extending ears 18. 10 Pivoted to the ears 18 are the arms of a stiff wire yoke 19.

On the covering 13 is an upstanding boss or the like 20. The bell crank locking lever 21 has one end of one arm pivoted to the boss 20. The central arm of the yoke 19 is extended through the bell crank locking lever 21 at the angle thereof, as illustrated in Figures 2 and 3.

These parts are so arranged that the cap can be swung up to position above the container and resting on the container, and the bell crank locking lever can then be swung down to the position shown in Figure 2, for resiliently locking the cap in place and holding the gasket tightly against the flange 12. When the locking lever 21 is in 25 this locking position, the cross member of the yoke 19 is slightly off center in one direction. By swinging the free arm of the locking lever upwardly, the cross arm of the yoke 19 may be swung over center, and a little farther movement 30 of the locking lever tends to raise the cover away from the container. The cover can then be swung free of the container to the position, for instance, shown in Figure 3 in dotted lines, and thence 35 downwardly to the side of the container, as shown in full lines in Figure 3.

On the ring 16 is a bracket 23, which may be bolted or screwed as for instance on the front side of the dash of an automobile, as illustrated in Figure 1. The container is intended to hold a 40 fuel, as for instance kerosene, and also one or more flares.

I shall now describe the preferred form of the flares to be used with the container.

The flare indicated at A in Figure 4 for example 45 comprises a container having a bottom half 24 and an upper half 25 welded or otherwise secured together at the top of the member 24 and the bottom of the member 25 along a rib 26. The under side of the container A is provided with an 50 up-struck or upset central part 27, which is preferably adapted to partially receive the burner of a lower flare when the flares are stacked (see Figure 2).

The upper member 25 of the flare A is formed 55

with a central wick opening 28 from which extends an upwardly extending wick tube 29. Each flare is provided with a burner comprising a lower tubular member 30, preferably welded to the lower part of the tube 29 on the outside thereof, and preferably flared toward its upper end. The upper half of the burner is in the form of an inverted cap 31 having its lower edge secured to the upper edge of the member 30, and provided 10 with an opening 32 in its top and with openings 33 in its wall.

The top of the member 25 of the flare body A is provided on one side of the wick tube with an up-struck portion 34 having an outlet vent 35. 15 On the opposite side of the wick tube is a down-struck portion 36 having an inlet vent 37.

A chain or other flexible device 38 is fastened preferably to the burner 30 and it may have a ring 39 at its free end.

20 I use an asbestos wick 41 mounted in the wick tube and extending down into the flare.

I preferably use two flares with each container. If the container is partially filled with a suitable fuel 40, such for instance as kerosene, the user 25 can take hold of the chain attached to the flare and let the flare down into the liquid. The next flare can then be dropped into the container, and pushed down until it sets on the lower flare, as shown in Figure 2. The amount of liquid preferably used is enough to stand well above the 30 part 34 of the upper flare when the flares are first put into the container.

By providing the raised opening 35 and the lowered opening 37, the flares will automatically 35 fill with liquid when immersed in it. The liquid will enter through the opening 37, and the air will emerge through the opening 35. The rings 39 of the chains are hung on the hook 22, the cap is locked in position, and the device is then 40 ready for transportation or storage.

When it is desired to use the flare, the cover is lifted and the ring for the upper flare is taken off the hook 22, and the flare is taken out. The other flare can similarly be taken out when desired. The flare can be lighted with a match and carried with the chain.

If the flare is used in connection with an automobile as a warning when the driver is compelled to stop on the highway, the flare can be set on the highway near the automobile in much the same manner that flares are used in connection with trucks.

Flares of this kind have, of course, a great variety of uses. The device is adapted for use by campers, workmen on construction jobs, and so on.

The construction herein disclosed has a number of advantages. It affords a flare which is very simple of construction and is economical to 60 make and use.

All that is necessary to replenish the fuel supply in the flare itself is to drop it into the container so that it is submerged to the point where it can take in a new supply of fuel. The user need not 65 have any contact with the fuel, because he can handle the flare by taking hold of the ring on the chain.

One important advantage of the construction 70 herein shown lies in the fact that the flares may be carried in a container without any particular means for locking them in position, and yet when the container has fuel in it, the flares will not knock against the walls to their injury or the injury of the walls, or in such a way as

to be noisy. The fluid will prevent any rattling. I claim as my invention:

1. In a construction of the kind described, a vertically elongated cylindrical container, a cover therefor adapted to close the container and form a liquid-tight seal therewith, a plurality of flares stacked in the container and adapted to be substantially submerged in fuel therein, each flare having a body with an upward inset center bottom portion and each having a burner projecting 10 upwardly into the bottom of the next upper flare, a flexible member connected to each burner near the lower part thereof, and means on the cover engaging and holding one end of each flexible member, the flexible members being quickly detachable at one end, each flare having in its top a down-struck portion and an up-struck portion each having an opening.

2. In a structure of the kind described, the combination of a liquid container having a removable tight cover with a plurality of disconnected separate flares arranged in stacked position in the container, each flare having an upwardly projecting burner, the flares having coacting parts to maintain them in stacked position, a flexible device detachably connecting each flare with said cover, whereby upon lifting the cover the flexible members may be conveniently used to remove the flares from the container.

3. The combination of a container having a body element and a removable tight cover element, with a plurality of flares stacked in the container, each comprising a hollow metal body with a burner at its top, and having spaced holes in the upper part of the hollow body spaced from 35 the burner for the passage of liquid fuel and gas and air, the flares having coacting parts to permit their being stacked without closing said holes.

4. The combination of a container having a body element and a removable tight cover element, with a plurality of flares stacked in the container, each comprising a hollow metal body with a burner at its top, and having spaced holes in the upper part of the hollow body spaced from 45 the burner for the passage of liquid fuel and gas and air, the flares having coacting parts to permit their being stacked without closing said holes, and flexible members connected to the respective flares, with their free ends supported adjacent the upper part of the container.

5. The combination of a container having a body element and a removable tight cover element, with a plurality of flares stacked in the container, each comprising a hollow metal body 55 with a burner at its top, and having spaced holes in the upper part of the hollow body spaced from the burner for the passage of liquid fuel and gas and air, the flares having coacting parts to permit their being stacked without closing said 60 holes, and flare lifting members connected to the respective flares with their free ends adjacent the upper part of the container.

6. The combination of a container having a body element and a removable tight cover element, with a plurality of flares stacked in the container, each comprising a hollow metal body with a burner at its top, and having spaced holes in the upper part of the hollow body spaced from 65 the burner for the passage of liquid fuel and gas and air, the flares having coacting parts to maintain them in stacked position without closing said holes.

7. In a structure of the kind described, the combination of a liquid container having a re- 75

movable tight cover with a plurality of disconnected separate flares arranged in stacked position in the container, each flare having an upwardly projecting burner, the flares having coacting parts to maintain them in stacked position, a flexible device detachably connecting each flare with said cover, whereby upon lifting the cover the flexible members may be conveniently used to remove the flares from the container, each flare having spaced holes in its top for the passage of fuel, gas and air.

8. In a structure of the kind described, the

combination of a liquid container having a removable tight cover, with a plurality of disconnected separate flares arranged in stacked position in the container, each flare having a body and an upwardly projecting burner, the body of each flare being provided in its upper part with holes spaced from each other and from the burner for the passage of fuel, gas and air, the flares having coacting parts to maintain them in spaced position without closing said holes.
